UNITED STATES PATENT OFFICE.

WILLIAM S. PRIDE, OF OAKLAND, CALIFORNIA.

REINFORCEMENT FOR PLASTERING.

1,167,837.

Specification of Letters Patent. Patented Jan. 11, 1916.

Application filed December 21, 1914. Serial No. 878,255.

To all whom it may concern:

Be it known that I, WILLIAM S. PRIDE, a citizen of the United States, residing at Oakland, in the county of Alameda and State of California, have invented new and useful Improvements in Reinforcement for Plastering, of which the following is a specification.

This invention relates to plastering and the art of applying a plastic material, which will afterward harden, to walls and surfaces, and particularly to a means for reinforcing such plastic surfaces where they meet to form corners.

15 The invention consists of metallic angle pieces fixed to the inner corners or angles of rooms, projecting at substantially right angles parallel to the lathing forming the corners, and fixed thereto; the sides of said 20 corner pieces being bent or curved inwardly with the radius of curvature located outside of the angular strips, and parallel with their length, so as to form longitudinal arches which are perforated for the admission of 25 the plastic material to the spaces between the strips, laths and studding, and form a firm and rigid reinforcement for the wall surface material.

The invention consists of the parts and 30 the construction and combination of parts as hereinafter more fully described and claimed, having reference to the accompanying drawings, in which—

Figure 1 is a perspective view of a portion 35 of a corner reinforcing plate. Fig. 2 is a horizontal section of such a reinforcement, showing its attachment to the studding and the mortar application.

Some difficulty is encountered in properly 40 reinforcing plastered corners meeting on interior angles, and preventing separation or cracking, and my invention is designed to overcome this difficulty.

The interior corners of rooms are formed 45 by studding or equivalent structure A, upon which laths A' are nailed. In my invention strips or plates, preferably of sheet metal 2, are stamped out and bent to form the required angle 3, which fits into the 50 built up corner, and the two sides of the plate extend respectively along the corner work where they are nailed or fixed to the lathing A'. At points a short distance from the angle, these plates are arched inwardly, 55 as at 4, thus forming spaces between the

arched portions and the surface of the wood beneath. Holes or openings of suitable or convenient shape are formed through the plates so that when the plastic material is laid upon the wall and extended into the 60 corner, it will cover the plate and a portion will be forced through the openings into the channels beneath the arches, and also through the interstices between the laths, and being thus united with the main portion 65 of the surface material through the openings, a strong reinforce and bond is formed to retain the material in position and prevent injury from warping or shrinking 70 of the heavier exterior wood or studding support. This construction practically forms a rigid union between the lathing and plaster at the internal angles of rooms and insures the plaster against cracking, because any shrinking or change of position 75 of the studding will withdraw the light lath nails so that spaces may be formed between the laths and studding, but the plaster and laths will remain firmly together.

Having thus described my invention, what 80 I claim and desire to secure by Letters Patent is—

A reinforcement for interior plastered corners consisting of a plate bent at an angle to fit the interior corner and to form angularly disposed sides, each side being arched inwardly adjacent the angle of the plate to form vertical channels and to form with the sides of the angle a corner vertical channel having a restricted vertical inlet formed 85 by the arched portions, each arched portion having a vertical series of openings opposing those of the other arched portion for admitting plastic material to fill the first channels and permit of the formation 90 of a series of continuous cross bars of plastic material extending across the angle formed by the plate sides and connecting the material in all of the vertical channels, whereby the plastic material is doubly secured by either of the first vertical channels and the corner channel.

In testimony whereof I have hereunto set my hand in the presence of two subscribing witnesses.

WILLIAM S. PRIDE.
